US00D927638S

(12) **United States Design Patent** (10) **Patent No.:** **US D927,638 S**
Cocks et al. (45) **Date of Patent:** **** Aug. 10, 2021**

(54) **SHOWER ROSE**

(71) Applicant: **Phoenix Industries Pty Ltd**, Bayswater (AU)

(72) Inventors: **Andrew John Cocks**, Bayswater (AU); **Ban Hsi Liu**, Bayswater (AU)

(73) Assignee: **Phoenix Industries Pty Ltd**, Bayswater (AU)

(**) Term: **15 Years**

(21) Appl. No.: **29/702,800**

(22) Filed: **Aug. 22, 2019**

(30) **Foreign Application Priority Data**

Feb. 22, 2019 (AU) 201910942
(51) **LOC (13) Cl.** **23-01**

(52) **U.S. Cl.**
USPC **D23/213**

(58) **Field of Classification Search**

CLAIM

The ornamental design for a shower rose, as shown and described.

DESCRIPTION

FIG. 1 is an isometric bottom view of a shower rose according to our new design;

FIG. 2 is an isometric top view thereof;

FIG. 3 is a top view thereof;

FIG. 4 is a front view thereof;

FIG. 5 is a side view thereof, the opposite side view being identical;

FIG. 6 is a bottom view thereof;

FIG. 7 is an isometric side view thereof;

FIG. 8 is an enlarged view of a portion of the shower rose indicated in FIG. 7; and,

FIG. 9 is an enlarged view of a portion of the shower rose indicated in FIG. 2.

The views not shown form no part of the claimed design.

1 Claim, 5 Drawing Sheets
